COUNTERBORE

Walter Van Benschoten, Santa Monica, Calif.

Application July 20, 1945, Serial No. 606,167

2 Claims. (Cl. 77—58)

1

The invention relates to a counterbore and has for an object to simplify and improve the construction whereby different pilots and counterbore tools may be readily used with the same holder and in particular, whereby different tools or a selected tool may be assembled onto or removed from a holder-pilot unit with facility.

For further details of the invention reference may be made to the drawings wherein—

Fig. 1 is a view in elevation of a counterbore according to the invention.

Fig. 2 is a partial sectional view through the lower part of the tool of Fig. 1.

Fig. 3 is a sectional view on line 3—3 of Fig. 2.

Fig. 4 is an exploded view of the tool of Fig. 1.

Referring in detail to the drawings, the holder 1 has a coaxial threaded bore 2 to receive the threaded end 3 of a pilot 4. Various sizes of pilots may be used. The counterbore tool 5 slidably fits the holder-pilot unit, so that the counterbore 5 can be assembled on or removed from the holder 1 and pilot 4 without removing pilot 4 from the holder 1. Various sizes of counterbore tools like 5 can be used with the same holder and pilot.

The invention provides for assembling or removing the counterbore 5 with facility by providing for the application of pressure from the holder to the counterbore without thereby tightening the lock therebetween as in the case of a tapered shank and socket.

The counterbore tool 5 at its inner end is milled out, to provide a socket or recess 6 while leaving projections 17 and 18, the opposed inner walls 14 and 15 of which are parallel and flat, at opposite sides of the tool axis, to provide rotative engagement with the holder 1. The lower end of holder 1 is cut away to provide parallel flats 16, 16' which fit in recess 6 between the tool flats 14 and 15.

The recess 6 between projections 17, 18 has a shoulder or end 7, extending in a plane at right angles to the tool axis. The end 8 of holder 1 bears on shoulder 7, and extends between projections 17, 18, the holder 1 being of smaller diameter than tool 5. Working pressure along the axis of holder 1 is applied to tool 5 by the end 40 of holder 1 bearing on shoulder 7.

An additional pressure surface across the axis is provided as follows. The height of the projections 17 and 18 is greater than the height of holder flats 16, 16' and the opposite shoulders like 19 on holder 1 rest and fit in the opposite recesses like 9 in the outer ends of projections 17, 18 when the end of holder 1 fits between projections 17 and 18 and rests on the tool end or shoulder 7. The periphery of the two recesses like 9, in a

2

plane across the tool axis, lies on a circle having a diameter slightly larger than the diameter of the body of holder 1.

The tool 5 has a coaxial bore 13 to slidably fit the pilot 4.

The tool 5 is removably held in position on the holder 1 and on pilot 4 by a spring wire key 19, somewhat U shaped and having parallel legs 20, 21 which fit in parallel recesses 22, 23, each extending partly through one of the holder flats 16, 16' and partly through one of the tool flats 14, 15. The lateral ends of recess 6 house the bight and ends of wire key 19 within the periphery of tool 5.

The key 19 keeps the counterbore 5 from falling off from the holder 1 and pilot 4.

All of the non-circular rotative engagement flats 14, 15, 16, 16' lie in planes parallel to the tool and holder axis, whereby they are not locked together when axial working pressure is applied to the holder 1.

Various sizes of counterbore tools and pilots may be used with the same holder. Various other modifications may be made without departing from the spirit of the following claims.

I claim:

1. A counterbore comprising: a holder; a pilot; cooperating means on the pilot and in the holder, mounting the pilot coaxially in the holder; a counterbore tool having an axial bore through which the pilot extends, said pilot having a projecting end portion of a diameter less than that of the bore, whereby the tool may be slipped over the pilot while the pilot remains mounted in the holder, said tool having a recess in which the end of said holder is received, and having a shoulder against which the end of said holder abuts, said holder and tool having interfitting flats disposed in planes parallel to and on opposite sides of the tool axis and cooperating to transmit drive from the holder to the tool, and said holder and tool each having cooperating portions of key recesses opening into and parallel to the respective flats; and a U-shaped key having spaced legs received in the respective key recesses and having a bight connecting said legs, said tool being cut away between corresponding ends of said key recesses to house said bight.

2. A counterbore comprising: a holder; a pilot extending coaxially therefrom; a counterbore tool having an axial bore through which the pilot extends, said pilot having a projecting end portion of a diameter less than that of said bore, whereby the tool may be slipped over the pilot, said tool having a recess in which the end of said

holder is received, and having a shoulder against which the end of said holder abuts, said holder and tool having interfitting flats disposed in planes parallel to and on opposite sides of the tool axis and cooperating to transmit drive from the holder to the tool, and said holder and tool each having cooperating portions of key recesses opening into and parallel to the respective flats; and a U-shaped key having spaced legs received in the respective key recesses and having a bight 10 connecting said legs, said tool being cut away between corresponding ends of said key recesses to house said bight.

WALTER VAN BENSCHOTEN.
